(Cl. D52—6)

FIG. 2

FIG. 1

FIG. 3

FIG. 4

FIG. 5

FIG. 6

FIG. 1 is a perspective view of the internal spline indicator gage embodying my new design.

FIG. 2 is a side elevational view thereof.

FIG. 3 is an end view as viewed from the dial indicator end of the gage.

FIG. 4 is a top view thereof.

FIG. 5 is an end view of the gage as viewed from the end opposite the dial indicator.

FIG. 6 is a bottom view of the gage.

The dominant features of my design reside in the portions shown in full lines.

The undisclosed side of the gage is substantially the same in appearance as the side shown.

I claim:

The ornamental design for an internal spline indicator gage, substantially as shown and described.
